[57] CLAIM

The ornamental design for a wildlife insulating guard, as shown and described.

DESCRIPTION

FIG. 1 is a perspective view of a wildlife insulating guard showing our new design in its closed configuration;

FIG. 2 is a perspective view of the insulating guard in its open configuration;

FIG. 3 is a top plan view of the insulating guard in its closed configuration;

FIG. 4 is a bottom plan view of the insulating guard in its closed configuration; and,

FIG. 5 is a side elevational view thereof, all side elevational views being the same or symmetrical, as the insulating guard is generally flat when viewed from this angle.
